CALLING DEVICE.

1,360,113.

Specification of Letters Patent. Patented Nov. 23, 1920.

Application filed June 23, 1915. Serial No. 35,752.

To all whom it may concern:

Be it known that I, WILLIAM KAISLING, a citizen of the United States of America, residing in Chicago, county of Cook, and State 5 of Illinois, have invented certain new and useful Improvements in Calling Devices, of which the following is a specification.

My invention relates to calling devices, and has to do more particularly with calling 10 devices such as are commonly used at telephone substations for controlling the automatic switches which are located at the central office by directive impulses to extend the connection from a calling substation to 15 a called substation through the agency of the said switches. My invention is preferably adapted to operate in conjunction with the so-called metallic or two-wire type automatic circuits in which the circuit of the line is 20 interrupted a number of times determined by the adjustment of the calling device.

One of the features of my invention is the provision of an improved governing device 25 and the novel method in which the governor device is connected with the power driving mechanism of the calling device. Another feature of my invention is the manner in which the impulse springs are controlled by the said driving mechanism of the calling 30 device.

It has been found from practice that a calling device of simple construction and one that does not readily get out of order is most desirable, and to this end I further 35 direct my invention by producing an improved device of the class described which will obviate the objectionable features heretofore found in calling devices and embody desirable features and advantages all in a 40 simple, efficient and economical manner, and to the accomplishment of this object and such others as may hereinafter appear the invention consists in the novel details of construction, parts and combination of 45 parts hereinafter described, and particularly pointed out in the appended claims, reference being had to the accompanying drawings in which I illustrate the calling device in the different views, and in which 50 views like reference characters indicate like parts, and in which—

Figure 1 is a face view of the calling device;

Fig. 2 is a rear view of Fig. 1;

Fig. 3 is a right end view of Fig. 2; 55
Fig. 4 is a top view of Fig. 2;

Fig. 5 is a bottom view of Fig. 2 with certain parts cut away;

Fig. 6 is a sectional view along the line 6-6 of Fig. 5; 60

Fig. 7 is a sectional view along the line 7-7 of Fig. 2;

Fig. 8 is a face view of the device with the finger hold connecting member removed;

Fig. 9 is a skeleton perspective view of 65 the governor mechanism;

Fig. 10 is a perspective view of the spool-shaped member which holds the parts of the governor;

Fig. 11 is a perspective view of the weight- 70 member of the governor;

Fig. 12 is a perspective view of the impulse springs;

Fig. 13 illustrates diagrammatically a well-known substation telephone circuit with 75 the calling device of my invention connected in circuit.

Referring now more in detail to my invention as illustrated, it comprises a main mounting plate 1, having a flanged portion 2 80 and a forwardly extending cup-shaped portion 3. A main shaft 4 extends concentrically through the bearing of the main mounting plate 1, and has a finger-hold actuating member 5 fastened to it in any suitable manner, it being preferably staked at its forward end to the said shaft 4. The finger-hold actuating member 5 is provided with a plurality of openings or finger-holds 6, preferably 10 in number and the number 85 indicating disk 7 is placed with its indicating numerals below the actuating member 5 and resting upon the flange 2, the said numerals corresponding with the finger-holds 6. The indicating disk 7 has a protective 90 disk 8 of transparent material such as glass placed in front of it so as to protect the said indicating disk. The members 7 and 8 are clamped to the flanged portion 2 by means of a tripod clamping member 9 which is 100 fastened in position upon the cup-shaped portion 3 of the mounting plate 1 by means of the screws 10.

The ten openings which form the finger-holds 6 are numbered 1, 2, 3, etc., to 0. The 105 calling device is adapted to transmit from one to ten impulses, the said numerals upon the indicating disk indicating the number

of impulses its corresponding hole is adapted to send through the agency of the impulse springs. I also provide a casing 11 for inclosing the forward portion of the device, 5 the said casing being fastened to the flanged portion 2 of the mounting plate 1 by means of the screws 12.

The actuating member 5 is provided with a card 16 and a transparent protecting disk 17, the said card 16 and protective disk 17 being held in place by means of a clamping ring 18 which is fastened to the actuating member 5 in any suitable manner, as by the screws 19 which have screw-threaded engagement with the member 5. A stationary finger stop 13 is mounted upon the flanged portion of the casing 11 by means of the screws 12. When the actuating member 5 is advanced in a clock-wise direction 10 the advancing finger of the operator engages the stop 13 and arrests the movement of the actuating member 5. A pin 14 is staked to the stop 13 and extends through the casing 11. A pin 15 is provided which is staked 15 to the member 5 and when the member 5 is at normal, the pin 15 rests against the pin 14 so that when the member 5 is advanced in a clock-wise direction, the pin 15 moves with the member 5 and the member 5 in being released restores in a counter-clock-wise 20 direction and its return movement is arrested by the pin 15 engaging the stationary pin 14. The two pins 14 and 15 are used as a stop to hold the motor spring under proper 25 tension, which will be more fully described in another part of this specification.

Referring now more particularly to the operating mechanism, the main shaft 4 extends through a spring barrel 20, which 30 closes a motor spring 21, the said spring being secured at its inner end to a hooked formed pin 22 upon the shaft 4; and the outer end of the spring 21 is secured to a pin 23, the said pin being fastened to the 35 inner wall of the spring barrel 20. The spring barrel 20 is a flanged cup-shaped member and is set in the opening 25 of the plate 1 and is fastened to the plate 1 in any suitable manner, but I preferably hold 40 it in place by swaging it into the opening of the plate. The actuating member 5 which is staked to the shaft 4, fits closely against the barrel 20 forming a cover for the same. To allow the proper tension to be given to 45 the motor spring 21, the actuating member 5 is revolved in a clock-wise direction until the motor spring is under proper tension. The stop 13 is then mounted upon the flanged portion 2 with its staked pin 14 projecting 50 through the casing 11, the pin 15 which is staked to the member 5 engaging the said pin 14, thus holding the motor spring 21 under proper tension.

Positioned next to the spring barrel 20 55 along the shaft 4 is the gear wheel 26 loosely

mounted upon the said shaft. A ratchet wheel 27 is positioned next to the gear wheel 26, the said ratchet 27 being rigidly fastened to the shaft 4 in any suitable manner as by a pin 28. The ratchet wheel 27 rests against the face of the gear wheel 26 and a pawl 29 pivotally fastened to the gear wheel 26 is operatively associated with the ratchet wheel 27, the said pawl being held against the said ratchet by means of a spring 30 which is also positioned upon the gear wheel 26, and held in place in any suitable manner. A gear wheel 31 is rotatably supported at its opposite ends to the plate 1 and to a bridge plate 32, the said bridge plate being secured to the studs 36, 37 and 38, by means of the screws 39. The said studs are staked to the plate 1 thus securely holding the plate 32 upon the main mounting plate 1. The gear 31 has a pinion 33 staked to it in any suitable manner, and this pinion 33 meshes with the gear 26. The gear wheel 31 meshes with a pinion 34 which is integral with the shaft 35 of the governor mechanism G, which is adapted to retard the return movement of the finger hold actuating member 5 to a predetermined speed.

The governor mechanism G comprises a main shaft 35 which is rotatably supported at its opposite ends in the plate 1 and the bridge plate 32. A pinion 34 is cut upon the shaft 35 and is shown in mesh with the gear 31. A spool shaped member 40 holds the governor mechanism which controls the speed of the calling device in its return movement. The governor comprises a weighted member 41, semi-circular in shape, being pivotally mounted between the two spool heads 42 and 43 by means of a pivoted pin 44. A coiled spring 45 is positioned upon the pin 44, one of its free ends bearing against the weighted member 41, and the other free end of the spring bearing against an adjustment pin 46. This adjustment pin 46 in conjunction with the spring 45 regulates the speed at which the governor may be driven and therefore of course the speed at which the calling device transmits the impulses. The adjustment pin 46 has a slotted head 47 so that the pin may be turned and is inserted into the openings 48 and 49 of the spool heads of the member 40. The pin 46 also has a shoulder 50 which forms a bearing surface while the pin is being adjusted to regulate the speed of the governor. The end 51 of the pin 46 is slotted and spread so that when the pin is in place and in a certain adjustment, it will stay so adjusted due to the frictional engagement with the opening 49. A portion of the body of the pin is eccentrically disposed, forming the eccentric portion 52 and one end of the spring 45 rests upon this part of the pin. A piece of fiber 53, or other suitable material, is securely held in the weighted mem- 130

ber 41 in close proximity to the fulcrum of the weight. The member 40 and the several parts above described as a whole is slipped over the shaft 35 and into a cup-shaped member 54, which is rigidly secured to the bridge plate 32 in any suitable manner and forms a containing member for the said governor mechanism G. The member 40 is held in position with its several parts 10 upon the shaft 35 by means of the set screw 55.

The governor mechanism G is operatively associated with the train of gearing comprising the gears 26 and 31, and pinions 15 33 and 34. Now when the member 5 is operated in a clock-wise direction to set the calling device to transmit a certain number of impulses, the gear 26 being loosely mounted upon the shaft permits the movement of 20 the shaft and ratchet also in a clock-wise direction so that the pawl 29 rides over the teeth of the ratchet wheel 27. Upon the return movement of the member 5 with the shaft 4 and ratchet 27, the pawl 29 being 25 fastened to the gear 26, engages one of the teeth of ratchet wheel 27, causing the gear to be carried with it, and this return motion is transmitted by the train of gearing to the governor mechanism G. The weighted member 41 being pivotally mounted by 30 the pivot pin 44 in the spool member 40 which is being rotated due to being fastened to the shaft 35, causes the member 41 to be forced out by centrifugal force against the tension of the spring 45. The piece of fiber 35 53 upon the member 41 is forced against the inside periphery of the cup 54, and as the said fiber 53 is held in close proximity to the fulcrum of the weighted member 41, the weight of the member 41 is multiplied in 40 assisting the fiber 53 to remain in frictional engagement with the inside periphery of the cup 54 against the tension of the spring 45, thus permitting the device in its return movement to restore at a predetermined speed. In practice, it has been found that a group of impulses, ten in number, may be sent in a space from three fourths to one and one half seconds of time, and to permit 45 the calling device to operate within these limits, I provide adjustable means for the governor in the form previously described. Now should it be desired that the device run at a speed so as to transmit ten impulses 50 in say one and one-half seconds, the adjustable pin is turned until the eccentric 52 is at its lowest point so that the end of the spring 45 rests upon this lowest point of the eccentric and in this position the spring 45 55 is under the least tension so that upon the return movement of the device the weighted member 41 is more easily acted upon by centrifugal force causing the fiber to be held firmly in frictional engagement against the 60 inside of the periphery of the cup 54. Now

when the device is to be speeded up, the adjusting screw may be turned causing the spring end of the spring 45 to ride upon the eccentric until the eccentric is at its highest point, and in this position of the eccentric 70 causes the tension of the spring 45 to be increased. The resultant force acting upon the member 41 is decreased due to the increased tension of the spring 45, so that the frictional engagement of the fiber 53 and the inside periphery of the cup 54 is not as great as in the former case, thus permitting the speed of the return movement to be increased and also permit a much shorter period for each impulse. 75

The gear 26, ratchet 27 and pawl 29 are so related that when the member 5 is moved slowly in a clock-wise direction the pawl 29 remains in engagement with a tooth of the ratchet 27 due to the tension of the spring 30, so that movement is transmitted to the governor mechanism G through the agency of the train of gearing. Now should the member 5 be rotated rapidly in a clock-wise direction, the pawl 29 will pass over 80 the teeth of the ratchet 27 and the gear being loose upon the shaft 4 remains stationary and no movement is transmitted to the governor mechanism G. I provide this arrangement as ordinarily the member 5 is 85 rapidly rotated in a clock-wise direction by an operator in sending a series of impulses and if this escapement were not provided the governor would tend to retard the forward movement of the dial to a slight extent, but 90 with this escapement provided I allow the rapid movement in a clock-wise direction of the member 5 without operating the governor mechanism. 95

In order to operate the impulse springs 105 of the device, I preferably provide an actuating ratchet 56 insulatingly mounted upon the main shaft 4 and having a plurality of teeth, 12 in number. I use only ten of these teeth as I only have the finger-holds numbered 1 to 10, having a space equal to two finger holds upon the member 5 and the stop 110 13 is so located that when impulses are being sent a slightly greater movement than that required to operate the impulse springs 115 a number of times depending upon the number of impulses to be sent is given to the member 5, this being so arranged that the positive action is obtained so that the full number of impulses are always transmitted. 120

Impulse contacts are provided which are interrupted according to the number of impulses to be transmitted, therefore I provide a pair of normally closed contacts. One of the contacts is in the form of an adjustable 125 contact screw 60, which has screw-threaded engagement with a lug 61 which is integral with the L-shaped member 62, this member 62 being insulatingly mounted upon the plate 32 and held in place by the insulated 130

screws 63. A screw 64 having screw-threaded engagement with the L-shaped member 62 forms a terminal for the adjustable contact 60. The other contact of the impulse springs 5 is in the form of a spring 65 which is insulatingly mounted upon the bridge-plate 32 by means of the insulated screws 66 and the clamping plate 67. A screw 68 has screw-threaded engagement with the plate 67 and forms a terminal of the contact 65. I so arrange the impulse contacts that the duration of interruption and contact of the impulse contacts 60, 65, may be varied and to this end I provide the adjustable contact 60 which may be moved inwardly or outwardly in the lug 61. When the contact screw is turned so as to move the contact away from a spring 65 the duration of interruption will be increased and when moved toward the spring the duration of the interruption will be decreased. A pawl 69 and the spring 65 are operatively associated with each other and are connected so as to form a hinged point 70. A spiral spring 71 holds the pawl 25 and spring in hinged relation, the said spring 71 having one end fastened to a hook 72 which is preferably integral with the spring 65. The other end of the spring 71 is fastened to a hook 73, which is integral 30 with the pawl 69, the spring 71 holding the pawl 69 against the teeth of the ratchet 56 which is insulatingly mounted upon the shaft 4. Now if the actuating member 5 is rotated in a clock-wise direction, the pawl 35 69 rides over the teeth of the ratchet 56, but on the return movement, the nose of the pawl engages a tooth of the ratchet and the spring 65 is drawn forward against its normal tension thus opening the normal contacts 60, 65, and due to the restering power 40 of the motor spring 21, the nose of the pawl 69 is forced upon the tooth of the ratchet it was engaging against the tension of the spring 71, and when the nose of the pawl 45 passes the teeth last engaged, due to the return movement of the shaft 4, the spring 71 draws the pawl into the next toothed depression of the ratchet to again close the contacts, the said contacts opening and closing 50 according to the number of impulses that are being sent.

I also provide a pair of shunt springs 75 and 76 by which the subscribers' apparatus may be short-circuited while the impulses 55 are being transmitted. The shunt spring 75 is insulatingly mounted upon the plate 32 by means of the insulated screws 63 and the clamping plate 62, the screw 64 forming the terminal for the shunt spring 75. The shunt 60 spring 76 is insulatingly mounted upon the bridge plate 32 by means of the insulated screws 78 and the clamping plate 79, the screw 80 having screw-threaded engagement with the plate 79 forming a terminal for the 65 spring 76. An operating stud 81 of insulat-

ing material is provided to operate the shunt springs and is positioned upon the shaft 4 next to the ratchet 56, the said stud 81 and the ratchet 56 being held in a position upon one end of the shaft 4, by means of a washer 70 82, and a nut 83, the said nut 83 having screw-threaded engagement with the end of the shaft 4. The stud 81 is normally in engagement with the projecting portion of the shunt spring 76 whereby the said shunt 75 spring contacts are held normally out of engagement, but when the shaft 4 and actuating member 5 are moved off normal, the stud 81 moving with the shaft 4 disengages the end of the spring 76 allowing the contacts 80 75, 76 to engage, the contacts remaining in engagement until the member 81 returns to normal. The lugs 86 upon the bridge plate 32 are provided to form means for fastening the dial to an instrument. In Fig. 13, I 85 have illustrated a well-known substation with a calling device of my invention connected in circuit. I have used like reference characters for indicating the parts, which are the same as in the rest of the drawings, 90 so that the coöperation of the impulse and shunt springs will be easily understood.

I will now describe briefly the operation of the device. Let us assume that the operator wishes to effect four operations of the 95 impulse contacts 60, 65, that is to transmit four impulses, the finger of the operator will be inserted into the finger-hold 6 above the number 4 and the member 5 is rotated in a clock-wise direction until the finger of the 100 operator engages the stationary stop 13. The rotation of the member 5 also causes the rotation of the main shaft 4 and also the ratchet 27 and as the driving gear 26 is loose upon the shaft 4 and as pawl 29 is 105 mounted upon the gear 26, the ratchet in its rotation allows the said pawl to pass over the teeth of the ratchet. The pawl 69 which is operatively associated with the impulse spring 65 also passes over the teeth 110 of the impulse ratchet 56 but not affecting the impulse springs at this time. As the main shaft 4 leaves normal the stud 81 carried thereby disengages the projection of the shunt spring 76 allowing the said spring 115 to engage the shunt spring 75 to close the said springs to short circuit the substation apparatus. The adjustment of member 5 also winds up the motor spring 21 so that when the finger of the operator is removed 120 from the finger-hold of member 5, spring 21 restores shaft 4 and ratchet 27. The pawl 29 now engages a tooth in said ratchet and said ratchet carries the gear 26 with it and this motion is transmitted to the governor 125 mechanism G through the agency of the train of gearing, thus allowing the restoration of the device at a predetermined speed. Upon the return movement of the shaft, the ratchet 56 affects the pawl 69 as previously 130

- described to cause the contacts 60, 65 to be interrupted four times to transmit the proper number of impulses. Upon this return to normal of the device the stud 81 again engages the projection of spring 76 again interrupting shunt springs 73, 76. The device is now at normal and is again ready to be adjusted to effect the transmission of another set of impulses.
- 10 In illustrating my invention, I have shown it operating with a certain form of substation, but I do not wish to be limited to this as the device of my invention is adapted for other uses. I also do not wish to be limited to the exact structure as shown as many modifications and changes may readily suggest themselves, but I aim to cover all such changes as come within the spirit and scope of the appended claims.
- 20 Having described my invention, what I desire to secure by United States Letters Patent, is:
1. A calling device comprising a mounting frame, impulse mechanism supported by a bridge-plate mounted upon the rear of said frame, a circular cup-shaped member secured to said frame and extending forward past the face of said frame, and a rotatable finger-hold setting member operatively connected to said impulse mechanism and lying within the said cup-shaped member.
  2. A calling device comprising an integral cup-shaped mounting frame, impulse mechanism supported by said frame and positioned partially within the cup portion of the frame, a flanged cup-shaped shell secured to said frame and extending forward past the external face of the cup portion of the frame, and a rotatable finger-hold setting member lying adjacent to the external face of said cup portion and positioned within the said cup-shaped shell member.
  3. A calling device comprising an integral cup-shaped flanged mounting frame, impulse mechanism supported by the frame and positioned partially within the cup portion of the frame, a rotatable finger-hold setting member positioned at the external face of the cup portion and connected to said impulse mechanism, and a circular member attached to said mounting frame extending around the outer perimeter of the said setting member.
  4. A calling device comprising impulse transmitting mechanism, a setting member for controlling the said impulse mechanism, a toothed impulse wheel directly connected to the said setting member, an impulse spring carrying a pawl for engaging the said impulse wheel, the said pawl being normally in engagement with said impulse wheel and adapted to operate said impulse spring a number of times corresponding to the adjustment of the setting member upon the return movement of the setting member to normal, said pawl being ineffective to operate said impulse spring upon the setting operation of the setting member.
  5. A calling device comprising an impulse sending mechanism, a rotatable dial for controlling said mechanism, a toothed impulse wheel connected to said dial, a pair of contact points adapted to be opened and closed responsive to the operation of said dial, and a catch member pivoted to one of said contacts and operatively associated with said impulse wheel for performing such opening and closing of said contacts upon the return movement only of said rotatable dial.
  6. A signaling device comprising impulse mechanism, a rotatable finger-hold device for controlling said impulse mechanism, a pair of contacts adapted to be opened and closed responsive to return operations only of said finger-hold device, one of said contacts being operatively connected to the finger-hold device through the medium of a pivoted catch member and the other of said contacts comprising an adjustable screw threaded member adapted to control the relation between said contact points.
  7. A calling device comprising an impulse mechanism including an impulse wheel, a setting member for controlling the impulse transmitting mechanism, a pair of contacts controlled by the said setting member, one of said contacts comprising a spring member provided with a pivoted ratchet pawl associated with said setting member, the other of said contacts comprising an adjustable screw-threaded member and a coiled spring for maintaining said ratchet pawl in its position in relation to said impulse wheel.
  8. A calling device including impulse transmitting mechanism, a setting member for controlling said mechanism, a serrated member connected to said setting member and adapted to rotate forward and backward, and a pair of contacts controllable by said setting member, one of said contacts including a pivoted catch member normally in engagement with said serrated member and adapted to be effectively operated only upon the backward rotation of said serrated member to open and close said pair of contacts.
  9. A calling device including impulse transmitting mechanism, a setting member for controlling said mechanism, a serrated member connected to said setting member and adapted to rotate forward and backward, and a pair of contacts controllable by said setting member, one of said contacts being provided with a catch member adapted to be ineffectively moved upon the forward rotation of said serrated member, but adapted to be effectively moved upon the backward rotation of said serrated member, a number of times, corresponding to the num-

ber of teeth of said serrated member that contacts with the said catch member to open and close said contacts.

10. A calling device including a mounting plate, impulse transmitting mechanism secured to said mounting plate, a setting member for controlling said impulse transmitting mechanism, a cylindrical member provided with a flange attached to the rear 5 of said mounting plate and extending forward flush with the face of said setting member whereby said setting member is protected against injury.
11. A device of the character described including a mounting plate, impulse transmitting mechanism secured to said mounting plate, a circular setting member connected to

said impulse transmitting mechanism for operating the same, a flanged cylindrical member attached to the back of said mounting plate and extending forward flush with the face of said circular setting member, a series of finger holds for said setting member, and a finger stop extending upward adjacent said cylindrical member and across in front 20 of said finger holds.

Signed by me at Chicago, county of Cook and State of Illinois, in the presence of two witnesses.

WILLIAM KAISLING.
